CONVEYER.

John W. Forsythe, Wilkinsburg, Pa.

Application May 11, 1936, Serial No. 79,129

4 Claims. (Cl. 193—35)

This invention relates to conveyers and more particularly to idle conveyers which employ idle rollers.

In steel mills, by way of example, the use of gravity conveyers, or so called "runways" is essential for the transfer of both hot and cold materials. These idle conveyers are made up of rollers with stationary side plates which prevent the material from leaving the rollers. Such conveyers are frequently used for transferring material to shears which are movable for regulating the place the cut is to be made. The movement of these shears results in the lengthening or shortening of the conveyers. This variance makes it difficult to support the rollers of the conveyer so that they will present an even contact surface to the material to be conveyed.

It is among the objects of the present invention to support a conveyer of the class described in such manner that the surface it presents to the material being conveyed is even; and also to prevent the material from leaving the rollers.

The foregoing and further objects will be apparent after referring to the drawings, in which:

25 Figure 1 is a plan of the apparatus of the invention.

Figure 2 is a sectional view on the line II—II of Figure 1.

Figure 3 is an enlarged fragmentary plan.

30 Figure 4 is an enlarged fragmentary elevation partly in section.

Figure 5 is a sectional view on the line V—V of Figure 4.

Referring more particularly to the drawings, 35 the numeral 2 designates a bed upon which there is slidably disposed a shear-housing 3. An elongated screw 4 is screw-threadedly disposed in the shear-housing 3 and rotated in any suitable manner to effect its sliding movement, whereby 40 it may be adjusted with respect to the end-roller 5 of a device which delivers the material to be sheared.

45 Adjacent the respective upper and lower blades 6 and 7 of the shear, the shear-housing 3 carries a vertically adjustable bed 8 in which there is mounted a rotatable roller 9. In order to enable the transfer of the material to be sheared from the end-roller 5 of the device which delivers it to and over the rotatable roller 9 on the 50 shear-housing 3, a conveyer employing idle rollers is provided. This conveyer is made up of a plurality of parallel shafts 12, each of which carries a roller 13. A pair of links 14 connects each end of adjacent pairs of parallel shafts 12. 55 These links 14 are apertured to permit the ends

of the shafts 12 to extend therethrough and are maintained in spaced parallelism by means of bushings 15.

5 Adjacent connected pairs of shafts 12 are connected by substantially rectangular frames which are open at their tops and bottoms. Each of these frames comprises a pair of inner and outer side members 17 and 18, respectively, which are beveled on their lower ends, as shown at 19. The inner and outer side members 17 and 18, respectively, of the frames are apertured adjacent their lower edges to receive the ends of adjacent link-connected shafts 12.

The inner side members 17 are mounted inside of the pairs of links 14, while the outer side members 18 are mounted outside of the same. The upper edges of the side members 17 and 18 of the frames are extended considerably above the rollers 13 in order to serve as side-guides whereby the material is prevented from leaving 20 the rollers.

The ends of each of the substantially rectangular frames are of different construction. That is to say, each frame is provided with a shallow end-wall 20 which extends downwardly but a 25 slight distance, and with a deeper end-wall 21 which extends downwardly to terminate adjacent the top surfaces of the links 14. The series of frames are so arranged that the shallow end-wall 20 of one abuts the deeper end-wall 21 of 30 another.

One end of the conveyer is attached, as at 23, to the vertically adjustable bed 8, while the other end is extended over a roller 25, which is adjacent the end-roller 5 of the device that delivers the 35 material to be sheared. The end of the conveyer which extends over the roller 25 depends downwardly into a well 26 where its free end is attached, as at 27, to a counterweight 28. This weight 28 is disposed in a guideway 29, and its 40 function is to prevent excessive sagging of the conveyer. Despite this, the elements of the conveyer tend to sag and present an uneven surface to the material being conveyed. This tendency is, according to the invention, prevented by the 45 contact of the outside surfaces of adjacent end-walls 20 and 21 of the rectangular frames, as shown at X; and also by the contact of the lower edges of the deeper end-walls 21 with the upper edges of the links 14, as shown at Y. The deeper 50 end-walls 21, by their contact with the upper edges of the links 14, prevent the shafts 12 and rollers 13 from raising when the shear-housing 3 is moved on the bed 2 by the rotation of the elongated screw 4.

While I have shown and described one specific embodiment of my invention, it will be understood that I do not wish to be limited exactly thereto, since various modifications may be made 5 without departing from the scope of my invention, as defined by the following claims.

I claim:

1. A conveyer comprising a plurality of parallel shafts, each pair of said shafts being connected 10 together adjacent their ends, a conveyer roll carried by each of said shafts, and means connecting adjacent connected pairs of shafts, said means being disposed adjacent the ends of said connected pairs of shafts and comprising a plurality 15 of normally stationary frames, each of said frames being constructed and arranged to provide seats for the ends of said connected pairs of shafts, one end of said conveyer being connected to a normally stationary support, the other end 20 of said conveyer being connected to a tensioning device whereby said conveyer presents a substantially flat conveying surface.

2. A conveyer comprising a plurality of parallel shafts, each pair of said shafts being connected 25 together adjacent their ends, a conveyer roll carried by each of said shafts, means connecting adjacent connected pairs of shafts, said means being disposed adjacent the ends of said connected pairs of shafts and comprising a plurality 30 of normally stationary frames, each of said

frames being constructed and arranged to provide seats for the ends of said connected pairs of shafts, and interlocking devices on the adjacent ends of said frames, one end of said conveyer being connected to a normally stationary support, the other end 5 of said conveyer being connected to a tensioning device whereby said conveyer presents a substantially flat conveying surface.

3. The combination with a roller conveyer employing side-links of a chain link comprising a substantially rectangular frame having spaced apertures for receiving the ends of a pair of adjacent rollers, one end of said frame being defined by a downwardly extending shallow end-wall, the other end of said frame being defined by an end 15 wall which extends downwardly to adjacent the top surfaces of the side-links of the conveyer.

4. The combination with a roller conveyer employing side-links of a chain link comprising a substantially rectangular frame having spaced apertures for receiving the ends of a pair of adjacent rollers, one end of said frame being defined by a downwardly extending shallow end-wall, the other end of said frame being defined by an end wall which extends downwardly to adjacent the top surfaces of the side-links of the conveyer, said frame having the lower ends of its side members beveled.

JOHN W. FORSYTHE.
